UNITED STATES PATENT OFFICE.

RAY E. FORDICE, OF CHICAGO, ILLINOIS, ASSIGNOR TO WILLIAM H. MINER, OF CHAZY, NEW YORK.

ROLLER SIDE BEARING.

1,226,202.

Specification of Letters Patent.

Patented May 15, 1917.

Application filed July 15, 1916. Serial No. 109,453.

To all whom it may concern:

Be it known that I, RAY E. FORDICE, a citizen of the United States, residing at Chicago, in the county of Cook and State 5 of Illinois, have invented a certain new and useful Improvement in Roller Side Bearings, of which the following is a full, clear, concise, and exact description, reference being had to the accompanying drawings, 10 forming a part of this specification.

This invention relates to improvements in roller side bearings.

The object of the invention is to provide a simple and inexpensive side bearing for rail- 15 way cars having means for automatically returning the roller to central or normal position after each actuation thereof.

In the drawing forming a part of this specification, Figure 1 is an end elevation of 20 portions of a body and truck bolster of a car showing my improvements in connection therewith. Fig. 2 is a longitudinal, vertical sectional view of the improved side bearing and taken substantially on the line 2—2 25 of Fig. 1. And Fig. 3 is a transverse, vertical sectional view taken on the line 3—3 of Fig. 2.

In said drawing, 10 denotes the body bolster of a car to which is swiveled the 30 truck bolster 11 in the usual manner. As shown, the body bolster 10 is provided with an integral striking plate 12 for coöperation, designated generally by the reference A.

The said bearing A comprises a base casting B and anti-friction roller C. The base casting B is of substantially hollow box-like 35 form with the side walls offset as indicated at 13—13 and the end walls curved as indicated at 14—14, to limit the travel of the roller C. The latter rides upon a steel insert 15 located in the bottom of the base casting B. The base casting B is secured to the truck bolster by suitable flanges 16 40 through which pass the rivets 17.

The offset portions 13 of the side walls of the base casting are provided to accommodate the movements of the trunnions or bosses 18—18 on the ends of the roller C.

At each end of the roller C, a bowed spring 50 19 is attached, as clearly indicated in Fig. 2. Each boss or trunnion 18 is longitudinally slotted as indicated at 20 and has slipped endwise therein the bent end of the spring 19. The opposite end of each spring 55 19 is riveted or otherwise suitably secured to the tread insert as indicated at 22. As shown, by the full and dotted lines in Fig. 2, the springs 19 are arranged oppositely, that is, one is bowed toward the right and 60 the other toward the left as viewed in said Fig. 2.

In operation, as the roller is moved from one side to the other, the springs 19 will be straightened out and upon release of the 65 pressure on the roller, the stored up energy in the springs 19 will automatically return the roller to central or normal position. The roller may be made in the form of a casting as can also the base member B. The 70 springs 19 may be cheaply manufactured and all the parts can be easily assembled as is apparent, thus providing a relatively inexpensive roller side bearing.

I claim:

1. In a roller side bearing, the combination with a base member, of a roller bodily movably mounted within said base member, and spring means for returning the roller to central position after each actuation thereof, said spring means comprising bowed springs, each secured at one end to the roller and at the other end to the base member.

2. In a roller side bearing, the combination with a hollow box-like base casting, of a roller mounted within said base casting, the roller having extended centrally located bosses at each end thereof, and a spring extending from each of said bosses to the base casting and connected to both, the springs being adapted to return the roller to normal position after each actuation.

3. In a roller side bearing, the combination with a hollow box-like base casting, the side walls of which are provided with centrally located offsets, of a roller mounted within said base casting and having bosses

extended from the ends thereof and working within said offset portions of the base casting, and a bowed spring at each end of the roller, each of said springs being connected at one end to one of said bosses and at its other end to the plate which sets in the base casting.

In witness that I claim the foregoing I have hereunto subscribed my name this 13th day of July 1916.

RAY E. FORDICE.
